[57] CLAIM

The ornamental design for a golf digital score keeper, as shown and described.

DESCRIPTION

FIG. 1 is front elevational view of a golf digital score keeper showing our new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof; and,

FIG. 7 is a left side elevational view thereof.

FIGS. 2-7 are drawn in enlarged scale for clarity of illustration. The broken line showing of glove and pad in FIG. 1 are for illustrative purpose only and forms no part of the claim.

FIG. 1

FIG. 5

FIG. 7
